HOT WATER HEATING SYSTEM WITH
PLURAL RISER CONTROL

John Edward Ercanbrack and Forrest A. Johnson, Chicago, Ill.; said Johnson assignor to Bell & Gossett Company, Chicago, Ill., a corporation of Illinois

Application April 28, 1930. Serial No. 447,996

5 Claims. (Cl. 237—56)

Our present invention relates to the provision of a hot water heating system with plural riser control for heating and distributing hot water for house heating purposes and also for service supply purposes.

The efficiency of oil, gas, and other mechanically operated and controlled burners in connection with house heating systems has now become pretty broadly recognized. Several plans have also been developed and disclosed for combining with a hot water house heating system provided with a mechanical burner means for heating water for a domestic or service supply for the same premises. These plans, pretty generally, involve the provision of an auxiliary casing through which the boiler water freely circulates and in which is disposed a coil included in the hot water domestic or service supply system.

In such combined systems it is generally proposed to connect the auxiliary casing with a return from the house heating system and to control the admission of hot water from the boiler to the house heating system by a thermostatically operated valve. A house heating system generally involves a plurality of risers from the boiler to the radiators and a like plurality of returns from the radiators to the boiler. The thermostatically operated valve is disposed in the circulating system between the boiler and the place where the risers separate, so that when the valve opens the hot water flows from the boiler to as many risers as may be present in the house heating system. It is a characteristic of such combined systems to maintain the boiler water at a relatively high temperature requisite for heating the domestic or service water supply, and the presence of this relatively high temperature boiler water renders the house heating system considerably quicker and more effective in action when the thermostatically operated valve opens for permitting the boiler water to flow into the house heating system and the radiators.

However, in such systems, when the weather is mild, the temperature of the water in the radiators falls below the temperature of the water returning from the auxiliary casing to the boiler, in which event a reverse circulation not infrequently develops in the house heating system commencing with the return to which the auxiliary casing is connected flowing up through the radiator or radiators to which that return is connected through the branched risers to the several radiators and back through another return or returns, which are generally present in

the system, to the boiler. This reverse circulation heats the house unduly in mild weather and when once established blocks and delays a normal circulation when the thermostat calls for hot water in the house heating system.

Our present invention has for its object the prevention of the creation or development of such a counter-circulation as above described. Also the embodiment of our invention is of such a simple and practical nature as to permit of its employment with relatively simple changes in connection with already installed hot water heating systems employing mechanically fired heaters for supplying heated water for service and domestic uses.

We have attained the foregoing objects and results by means of the structure illustrated in the accompanying drawing, in which—

Fig. 1 is a schematic illustration of such combined hot water house heating and service supply heating systems embodying our invention;

Fig. 2 is a fragmental, central, vertical section through our improved valve construction; and

Fig. 3 is a section on line 3—3 of Fig. 2.

Similar reference characters refer to similar parts throughout the respective views.

The hot water house heating systems to which our invention is applicable comprise a boiler 5 heated by an oil burner 6, or some other form 85 of mechanically operated burner, which is electrically controlled by an aquastat 7 for maintaining the boiler water at a predetermined temperature. From such a boiler comes a riser 8, which is usually branched to lead to different portions of the premises to be heated.

We provide the riser 8 with a T 9 which connects by means of a pipe 10 with the top of an auxiliary casing 11, the bottom of which connects through a pipe 12, elbow 13 and reducing T 14 with one of the usual returns 15 to the boiler.

Within the casing 11 is a coil *a* having independent connections exterior of the casing with piping *b* flowing to, and piping *c* returning from, a hot water storage tank *d*. The tank *d* is provided with an outlet *e* connected with the piping for supplying the premises with hot water and with an inlet *f* connected with the water service supply of the premises.

At or above the level of the connection of the pipe 10 with the auxiliary casing 11 the casing 11 is provided with a plurality of inwardly extending, radially disposed stub tubes 16, the inner ends whereof constitute faces of a common conical development adapted to be closed and 110

opened simultaneously by a single conical valve 17. The outer ends of the respective stub tubes 16 are connected with risers 18 and 19 leading respectively to radiators 20 and 21. The radiator 20 connects with return 22 connecting with the reducing T 14 and, radiator 21 connects with return 23 reaching the boiler independently.

The valve 17 is provided with a stem 24 which extends upwardly from the valve through suitable packing appliances 25 in the cover 26 of the auxiliary casing 11. Upon the cover 26 is mounted a motor 27 and associated equipment for opening and closing the valve 17 through the stem 24, the operation of which motor is controlled through a thermostat 28 located in the premises to be heated.

It will now be seen that with our combined systems of hot water house heating and service water heating it will be impossible, no matter how cold the water in the radiators may get, for a counter-circulation to arise through return 22, radiator 20, riser 18, riser 19, radiator 21 and back to the boiler through return 23, as risers 18 and 19 are simultaneously and positively closed when they are not supplying radiators 20 and 21 with hot water.

Having described our invention what we claim as new and desire to secure by Letters Patent is:

1. In a hot water heating system, a boiler, a plurality of risers and a plurality of returns having connection with said boiler, heat transfer elements included and establishing communication between said risers and returns, and means for simultaneously opening and closing said respective risers with respect to said boiler and with respect to each other.

2. A hot water heating system including a boiler, a feed from said boiler, a plurality of returns to said boiler, an auxiliary casing connected with

the feed from said boiler and one of the returns thereto, a plurality of radially disposed inwardly extending stub tubes associated with said auxiliary casing, and a single valve co-operating with the inner ends of said respective tubes whereby they may be closed from communication with said casing and with each other, risers connected with said stub tubes and heat transfer elements connecting and establishing communication between said risers and returns.

3. A hot water heating system comprising a boiler, a plurality of risers from and returns to said boiler, heat transfer elements connecting and establishing a circulation between said risers and returns, and means for simultaneously closing said respective risers with respect to said boiler and with respect to each other.

4. In combination a boiler, an auxiliary casing connected to the top and to the bottom of said boiler, said casing having a plurality of discharge ports therein, risers connected with said discharge ports, radiators connected with said risers, returns from said radiators to said boiler, and means for simultaneously opening or closing said discharge ports with respect to said boiler and with respect to each other.

5. In a hot water heating system, a boiler, a plurality of risers from and returns to said boiler, heat transfer elements connected and establishing a circulation between said risers and returns, said risers and returns constituting a plurality of complete circulating circuits, and a single means for controlling said respective circulating circuit with respect to each other and with respect to said boiler.
